[57] ABSTRACT

There are provided radiolabeled enzymes, namely 99^m Tc-Streptokinase and Urokinase which have thrombolytic activity and in view of their propensity to accumulate at the location of the thrombi provide an efficient means of locating said thrombi.

11 Claims, No Drawings

NOVEL COMPOSITIONS FOR RADIOTRACER LOCALIZATION OF DEEP VEIN THROMBI

FIELD OF THE INVENTION

Radiolabeled thrombolytic enzymes.

DESCRIPTION OF THE PRIOR ART

The location of thromboembolisms in the vascular system has long been considered a problem to which rapid and accurate solutions are desirable. One of the techniques which has been employed has been injection of radiotracer materials into the blood stream generally (Griep, Radiology, 97, 311, 1970). In this work radioisotopes were tracked throughout the system where the embolism is believed to reside. Since the location of the venous system in the human body is fairly well known, the blockage of flow of radiotracer indicates the location of the occlusion. This method however does not permit the rapid and accurate localization of the embolisms. ^{125}I labeled fibrinogen has been used in the detection of thrombi (Flanc, et al., Brit. J. Surg. 55, 742, 1968 and O'Brien, Lancet, 396, 1970). Unfortunately, fibrinogen cannot be incorporated into or attracted to an existing thrombus, thus limiting the concentration of detectable radioactivity. It would therefore be desirable to label a physiologically acceptable material which is attracted to and incorporated in a thrombo embolism giving rise to a high concentration of radioactivity at that point. Concomitant therewith it would be necessary to utilize a labeling isotope of high photon flux within acceptable patient radiation adsorbed dose limits, which had a half-life sufficient to permit circulation throughout the vascular system.

Among the radio isotopes which fulfill the criteria set forth above are ^{131}I and $^{99\text{m}}\text{Tc}$. Without question $^{99\text{m}}\text{Tc}$ is the most desirable of these radio isotopes. Because of its short physical half life, larger quantities of radioactivity (ie 15 mCi against 300 μCi for ^{131}I) thereby increasing the photon flux while maintaining a level of radiation which can safely be absorbed by the patient.

Much work has been done recently on the incorporation of $^{99\text{m}}\text{Tc}$ into human serum albumin which is a protein. The reported work in this area indicates that the reaction conditions for labeling human serum albumin with $^{99\text{m}}\text{Tc}$ are extremely sensitive. Care must be taken on the one hand to avoid conditions which lead to the denaturation of the protein and on the other hand which lead to the absorption of a substantial portion of the radioisotope on side-products of the reaction, such as colloidal stannous hydroxide. The problems in this work are mentioned in Eckelman, et al., Journal of Nuclear Medicine, 12, 707, 1971; Lin, et al., J. Nucl. Med., 12, 204, 1971; all of these workers have shown that the proportion of stannous chloride as a reducing agent is critical to the success of coupling the radioisotope to the protein.

Eckelman confirms the findings of Richards, Jap. Nucl. Med., 7, 165 (1968) that the removal of stannous hydroxide formed in the course of the reaction is highly advantageous since apparently some radioisotope is occluded upon or in the colloidal stannous hydroxide. Eckelman suggests that the optimum conditions of labeling human serum albumin comprise treating the serum albumin with stannous chloride, adjusting the pH to between pH 2 and pH 6, removing any un-bound

stannous chloride or stannous hydroxide, and then adding the pertechnetate.

SUMMARY OF THE INVENTION

5 The invention described herein was made in the course of work under a grant or award from the Department of Health, Education and Welfare.

10 There is provided Streptokinase and Urokinase covalently labeled with $^{99\text{m}}\text{Tc}$. In the process of preparing these labeled enzymes, a solution of $^{99\text{m}}\text{Tc}$ pertechnetate is added to the appropriate enzyme and treated with freshly prepared stannous chloride in dilute hydrochloric acid. The reaction mixture is buffered to a pH greater than 7 allowed to react for a few minutes and the unreacted anions removed, suitably by passage through an anion exchange column.

DESCRIPTION OF THE PREFERRED EMBODIMENTS

20 In the process of the present invention there is utilized as a starting material between 5,000 and 250,000 international units (hereinafter 5 to 250 Kiu) of Streptokinase or Urokinase. Streptokinase is generally preferred because of its greater availability. To this starting material is added $^{99\text{m}}\text{Tc}$ pertechnetate. There is added a quantity corresponding to initial radioactivity of from about 15 to about 20 mCi. The degree of dilution of the pertechnetate is not critical, however it is generally preferred to utilize an aqueous solution containing from about 5 to about 10 mCi per ml.

25 To this mixture of enzyme and pertechnetate is added freshly prepared stannous chloride in dilute aqueous hydrochloric acid. There may be utilized between 0.1 to about 4 mg. of stannous chloride in 1 ml. of between 0.1N and 2N HCl. It is generally preferred however to utilize from about 0.1 to about 0.5 mg. of stannous chloride in from about 0.1 to about 0.5N HCl. To this mixture is added an alkalinizing buffer. Any of the 30 commonly used alkaline buffers yielding a pH greater than 7 may be utilized. It is especially preferred however to utilize buffers having a pH between about 8 and about 12, resulting in a final solution pH between 7-8. There may be mentioned phosphate buffers, barbital buffers, and glycine buffers. (Teorell and Steinhagen J. Biol. Chem. 49, 183 (1921); Michaelis J. Biol. Chem., 87 33 (1930) and idem., Biochem Z. 234 139 1931; and Sorensen, Biochem Z. 21, 131 (1909) respectively) The mixture is allowed to stand for about 5 minutes and passed through an anion exchange column which will permit the radiolabeled enzyme solution to pass therethrough.

35 While applicants do not base their invention thereon, there is reason to believe that one or more $^{99\text{m}}\text{Tc}$ Technetium atoms are incorporated into the protein chain of the enzyme, probably by displacing the cyclic hydroxyl moiety or a ring hydrogen proximate thereto in the tyrosine segment of the protein.

40 In utilizing the novel Tc labeled enzymes of the present invention there are injected into the venous system between about 1 to about 10 ml. of solution having a radioactivity of between 1 and 20 mCi and bioactivity of between 80 and 350 Kiu.

45 Whole body scans are then taken at various time intervals e.g. $\frac{1}{2}$ to 4 hrs. past administration, using suitable detectors e.g. rectilinear scannings techniques or Anger Scintillation Camera studies. Thromboembolists

are indicated due to increased radioactivity at the site of the embolists.

EXAMPLE I

^{99m}Tc - STREPTOKINASE

To a vial containing 100Kiu Streptokinase is added 2 ml. of an aqueous solution of Technetium pertechnetate having a flux of 15 to 20 mCi. To this mixture is added 1 ml. of freshly prepared stannous chloride in hydrochloric acid (100 mg./liter, 0.2N), followed by 1 ml. of phosphate buffer (pH 12).

The mixture is allowed to stand for 5 minutes and passed through an anion exchange column (Dowex 1-X8, 2 cm X 10 mm. diameter column, 2 ml.). The coupled ^{99m}Tc-Streptokinase solution will pass through the column which will retain unreacted cationic material.

In accordance with the foregoing procedure but using Urokinase instead of Streptokinase there is obtained ^{99m}Tc-Urokinase.

I claim:

1. A radio labeled thrombolytic enzyme selected from the group consisting of ^{99m}Tc-Streptokinase and ^{99m}Tc-Urokinase.

2. ^{99m}Tc-Streptokinase, being a compound of claim 1.

3. ^{99m}Tc-Streptokinase, being a compound of claim 2 having an activity of between 0.8 and 2.5 mCi per 10 Kiu of Streptokinase.

4. A covalent compound of ^{99m}Tc and Streptokinase having an activity of between 0.8 to 2.5 mCi per 10 Kiu of Streptokinase.

5. ^{99m}Tc-Urokinase, being a compound of claim 1.

6. ^{99m}Tc-Urokinase, being a compound of claim 5 having an activity of between 0.8 and 2.5 mCi per 10 Kiu of Urokinase.

7. A covalent compound of ^{99m}Tc and Urokinase having an activity of between 0.8 to 2.5 mCi per 10 Kiu of Urokinase.

8. A method of preparing a radio labeled thrombo-

lytic enzyme selected from the group consisting of Streptokinase and Urokinase labeled with ^{99m}Tc which comprises the steps of:

a. treating from about 5 to about 250 Kiu of said enzyme with from about 15 to about 20 mCi of ^{99m}TcO₄,

b. adding to the mixture of Step (a) from about 0.01 to about 4 mg. of freshly prepared stannous chloride and hydrochloric acid,

c. raising the pH to between about 7 and 8 and, d. removing the unreacted pertechnetate from the mixture.

9. A method according to claim 8 which comprises the sequential steps of:

a. treating from about 50 to about 100 Kiu of Streptokinase with from about 15 to about 20 mCi of ^{99m}TcO₄,

b. adding to the mixture of Step (a) from about 0.1 to about 1 mg. of freshly prepared stannous chloride in from about 0.1 to about 1N hydrochloric acid,

c. adding to the acidic solution of Step (b) an alkaline buffer in an amount sufficient to raise the pH to between about 7 and about 8, and

d. passing the mixture of Step (c) through an anion exchange column.

10. A method of detecting thromboembolisms in a vascular system which comprises introducing into said vascular system under examination between about 8 and 350 Kiu of a physiologically acceptable solution of ^{99m}Tc labeled Streptokinase or Urokinase having a strength of between about 1 and about 20 mCi/Kiu and scanning said vascular system to determine the point of increased gamma radiation.

11. A method according to claim 10 wherein there is injected between about 8 and 350 Kiu of a physiologically acceptable solution of ^{99m}Tc labeled Streptokinase having a strength of between 1 and 20 mCi/Kiu.
